UNITED STATES PATENT OFFICE

2,441,314

DRIVING MECHANISM FOR IRONING MACHINES OR THE LIKE

Donald K. Ferris, Dayton, Ohio, assignor to General Motors Corporation, Dayton, Ohio, a corporation of Delaware

Original application November 30, 1940, Serial No. 367,989. Divided and this application January 7, 1944, Serial No. 517,403

13 Claims. (Cl. 74—277)

1

This invention relates to domestic appliances and more particularly to ironing machines.

This application is a division of my copending application S. N. 367,989, filed November 30, 1940, (Patent No. 2,363,518, granted Nov. 28, 1944) for Domestic appliance.

An object of this invention is to provide a mechanical movement for an ironing machine or the like with a unitary control causing rotation of one of the ironing members, closure of the gap between the ironing members, rotation or non-rotation of one of the ironing members when they have been closed upon each other, and a change of speed of rotation of one of the ironing members.

Another object of this invention is to provide an improved mechanism for driving the rotatable ironing member and for closing the shoe upon the rotatable ironing member.

Further objects and advantages of the present invention will be apparent from the following description, reference being had to the accompanying drawings, wherein a preferred form of the present invention is clearly shown.

In the drawings:

Fig. 1 is a vertical view, partly in cross-section, of my ironing machine;

Fig. 2 is a vertical view, partly in cross-section, taken transversely to Fig. 1;

Fig. 3 is an end view of the upper part of the ironing machine showing both shoes retracted;

Fig. 4 is a vertical cross-section showing the transmission mechanism;

Fig. 5 is a horizontal cross-section taken along the line 5—5 of Fig. 4;

Fig. 6 is a horizontal cross-section taken along the line 6—6 of Fig. 4;

Fig. 7 is a vertical cross-section taken along the line 7—7 of Fig. 5;

Fig. 8 is an elevational view of the mechanism shown in the lower part of Fig. 4;

Fig. 9 is a bottom view of a portion of the mechanism shown in Fig. 8;

Fig. 10 shows a detail of the mechanism shown in Fig. 8;

Fig. 11 is a horizontal cross-section taken along the line 11—11 of Fig. 8, showing the station clutch just before release of the shoe actuating cam from the drive mechanism;

Fig. 12 is a view similar to Fig. 11, but showing the cam in its fully released position;

Fig. 13 is a horizontal cross-section taken along the line 13—13 of Fig. 4;

Figs. 14, 15, 16 and 17 show the control pedal and its associated parts in the "stop," first speed,

2

second speed and "press" positions respectively;

Fig. 18 is an exploded view, in perspective, of the station clutch mechanism; and

Fig. 19 is a horizontal cross-section taken along the line 19—19 of Fig. 4.

The ironing machine may be mounted on a standard or table 10. It is provided with a rotatable ironing member or roller 11, a shoe structure including a relatively large shoe 12 and a relatively small shoe 13. The ironing members are closed upon and opened from each other and the ironing members are movable with respect to each other codirectionally to the surface of the large shoe. To this end, the rotatable member 11 is rotated under the control of a unitary controlling member, manipulator or pedal 14. The arrangement is such that the pedal 14, in various positions, causes either or both of the shoes to be closed upon the roller 11, causes the roller 11 to rotate at a plurality of speeds, or may cause the roller to remain stationary when the shoe structure has been closed upon it for pressing operations.

A motor 15 is provided for furnishing power to the parts controlled by the pedal 14. The motor 15 is connected to those parts through the medium of a transmission in the casing 16. This transmission is controlled by the pedal 14 to cause the roll driving shaft 17 to rotate at first and second speeds, and to rock the shoe actuating shaft 18 to bring the shoe structure into engagement with the roller 11.

The roller 11 is mounted on a stationary bearing shaft 19 and is driven by means of a rotatable shaft 20 keyed to the roller 11 at 21 and geared to the shaft 17 at 22.

The shoe structure is mounted on the rockable shaft 18. The large shoe 12 is secured to backwardly directed lugs 23 which are fulcrumed at 26 on the lever structure 24, which is loosely mounted on the shaft 18. Lever structure 24 is U-shaped in horizontal cross-section. A locking lever structure 25 is also fulcrumed at 26 and is provided with an extension 27 which may be brought into engagement with the end 28 of a leaf spring 29, the other end 30 of which is keyed and secured in the shaft 18. The arrangement is such that, when the lever structure 25 is pulled towards the user or to the left as viewed in Fig. 1, by means of the knob 31, the corresponding shoe is placed in condition for engagement with the roller 11 whenever the shaft 18 is properly rocked by the transmission mechanism. Another leaf spring 29' is keyed to the shaft 18 and is effective to retract the shoe when the shaft 18

is rocked clockwise. A more detailed showing and description of the shoe supporting mechanism is contained in my copending application S. N. 282-228 filed June 30, 1939, now Patent #2,363,517, to which reference is made, if necessary, for further disclosure thereof.

The small shoe 13 is supported on the shaft 18 by a structure similar to that which supports the shoe 12. Corresponding parts have been numbered with the same number provided with the suffix *a*.

The large shoe 12 and the small shoe 13 may be used together for flat work or the small shoe may be used alone for wearing apparel, as more fully described in my copending application S. N. 367,989. They may be selectively brought separately into engagement with the roller, or they may both be brought together into engagement with the roller by movement of the knobs 31 and 31a towards or away from the user and by subsequent movement of the pedal 14 to cause the motor to rock the shaft 18. When brought forward together, they form a large composite shoe useful in ironing flat work. The small shoe alone is specially adapted for ironing the collars, cuffs, sleeves, etc., of wearing apparel.

The shoe rocking shaft 18 is journaled in a stationary bearing carried by the upstanding casing 41. The roller 11, and its stationary bearing 19 are carried by the stationary casing 42, both cases being rigidly secured to each other and to the base 10, through the medium of the solid top 16a of the gear casing 16.

The shoe rocking shaft 18 is rocked by a downwardly extending member or lever 43. The lower end 44 of the lever 43 is reciprocated or rocked in a vertical plane by the extension 45 of the cam sleeve member 46. The cam sleeve member 46 is actuated by the cam 47, which may be rotated selectively to two positions substantially 180° apart, around stationary stub shaft 47a, on a vertical axis in said vertical plane by means of a station clutch arrangement hereafter described. The station clutch includes a ratchet wheel 48 which rotates about said axis all the time that the motor 15 is actuated. The ratchet wheel 48 is engaged by the pawl or tooth 49 while the cam 47 is being moved between its "station" positions, which are located substantially in said vertical plane, and the tooth 49 is automatically disengaged from the ratchet wheel 48 at the "stations" when the shoe structure is either fully retracted or fully brought forward. The station engagement and disengagement of the tooth 49 is controlled by a control member including the rotating levers 50 and 50a which rotate in different horizontal planes and come into the engagement with the end 51 of the rockable stop lever 52 which is selectively movable into said planes. As shown in Fig. 11, one of the levers 50 has just come into engagement with the end 51 of the lever 52. Referring to Fig. 18, along with Figs. 11 and 12, it is to be noted that the tooth 49 is carried by a slide 53 which fits over the cam 47 and is slidably secured thereto by means of screws 54 with the plate 55 interposed therebetween. Accordingly, when the ratchet wheel 48 rotates the tooth 49, slide 53, plate 55 and cam 47 in a counter-clockwise direction for a short distance after the lever 50 engages stop 51, the pin 56 is rotated relatively to the now stationary slot 51, causing the slide 53 to move outwardly (to the left in Figs. 11, 12 and 18). At the same time the tension on spring 58 is stretched between the now stationary ear 59 of the plate 55 and the

moving lug 47a rotating cam 47. This relative motion continues between the position shown in Fig. 11 to that shown in Fig. 12 at which time the cam 47 and plate 53 stop rotation because the tooth 49 becomes disengaged from the driving ratchet wheel 48.

It is to be noted that the slot 51 is wider than the diameter of the pin 56, as clearly indicated in Figs. 11 and 12. This prevents ratcheting of the tooth 49 with the ratchet 48 after the mechanism has reached the position shown in Fig. 12, because the tooth 49 can be knocked clear of the teeth of ratchet 48 due to the clearance play between pin 56 and slot 51.

The cam is maintained in the position shown in Fig. 12, by a leaf spring 60, carried by the sleeve 46, which spring 60 engages the teeth 61 formed in the periphery of the cam 47. These teeth are constructed to allow the cam 47 to move counter-clockwise with relation to the sleeve 46, but prevent backward movement thereof. Spring 60 and teeth 61 therefore function as a one-way clutch. The station stop is so selected that the cam 47 stops slightly before maximum outward movement of the sleeve 46 is produced, and at this time the tooth 49 is released. The leaf spring 60 then prevents backward movement of the cam 47 in spite of the strong backward pull by the spring 58 between the ear 59 and the cam 47.

The motor 15 drives the worm 62 which is meshed with the gear 63 and drives the driving shaft 64. This shaft is fixedly secured to the ratchet wheel 48 and also to a sun gear 65 which is part of a planetary gear drive for the roll rotating shaft 11. The planetary gearing is so constructed that when the first idler toothed ring 66 is stopped by the first control means or lever 67, the roll is rotated at one speed. When the second idler toothed wheel 68 is stopped by the second control means or lever 69, the roll is rotated at a different speed. The levers 67 and 69 are urged in a clockwise direction by springs 70 and 71 and in a counter-clockwise direction (Figs. 5 and 3) by the lost motion connection or slide 12 under the control of the manipulator or pedal 14. The slide 12 is provided with a notch 73, such that when the notch 73 is brought into positions opposite the ends of levers 67 and 69 respectively, the respective levers are permitted to be rocked clockwise by their respective springs 70, 71, into stopping engagement with the respective wheels 66 and 68. Thus it is to be seen that when the pedal 14 is moved to its various positions (see Figs. 14, 15, 16 and 17) the planetary gears are controlled by the levers 67 and 69 to hold the roll 11 in the stopped position when the pedal 14 is in its uppermost and lowermost position, and the roll 11 is rotated at first and second speeds when the pedal 14 is in its two intermediate positions.

It is to be noted that the shoes 12 and 13 may be used together as a unitary large shoe by moving the handles 31 and 31a forward to cause the leaf springs 29 and the spring of 31a corresponding to 29 to become effective on their respective shoes. Either one of the shoes 12 or 13 may be used independently of the other by moving one of the handles 31 or 31a forward while the other handle is in the back position. The small shoe 13 is particularly useful for ironing wearing apparel such as shirts or the like, and may be used with the same effect as a hand iron without the necessity of lifting the same. Because of the shape and size of the shoe 13, it is possible to iron collars, cuffs, etc., with very little practice

and in a manner quite similar to hand iron operation.

The two-speed planetary drive is connected to the shaft 17 by means of the planetary gear frame or spider 80 which is fixed to the shaft 17. The spider 80 carries first planetary gears 81 mounted on bearing pins 82. The gears 81 are meshed with the sun gear 65 and also with an internal gear 83 carried by the first idler ring or wheel 66. The gears 81 have integrally formed therewith smaller second planetary gears 84 which mesh with an internal gear 85 on the second idler ring or wheel 68. The wheels 66 and 68 are loosely mounted on bearings 67 and 69 respectively so that they are free to turn as long as they are not engaged by the stop rods 61 and 63. Therefore, as long as these rods are disengaged, no torque can be transmitted through the free running wheels 66 and 68, and the shaft 17 remains stationary. However, when the wheel 66 is held stationary, a relatively fast rotation is imparted to the roll 11, while a relatively slow rotation is imparted to the roll 11 when the wheel 68 is held stationary.

The station clutch is controlled from the pedal 14 by means of the slide 72. The slide 72 is provided with an ear 90 on top of which the end 81 of the stop lever 52 rests. The stop lever 52 is urged in a clockwise direction (Fig. 4) by means of the spring 92. When the slide 72 is in its highest position, as shown in Fig. 4, the end 81 of the lever 52 stops the lever 50 which holds the shoe structure away from the roller. As the slide 72 is moved to its next lower position, the end 81 of the lever 52 rises to engage the upper lever 50 and thus moves the station clutch structure to hold the shoe structure against the roll.

It is desirable to provide an "indexing" means so that the user may be conscious of the correct place to stop the pedal 14. To this end a U-shaped spring 94 is secured to the lower portion 95 of the casing 16. This U-shaped spring contracts into the notches 96, 97 and 98 in the slide 72. This cooperation between the spring 94 and the notches 96, 97 and 98 imparts an "indexing" feel to the user's foot, so that the pedal 14 is used in the four positions only.

Means are provided for raising the pedal when released by the user's foot. To this end a spring 100 is secured to a stationary part of the ironing machine, such as to the lug 101 of the casing 16, and the other end of the spring 100 is secured to an intermediate part 102 of the rod 103 which connects the pedal 14 to the slide 72. The rod 103 is connected to the slide 72 by means of a bolt 104. The slide 72 is held from lateral displacement by the bolts 105 which are loosely fitted in the slots 106 of the slide 72 and are carried by stationary parts of the casing, such as the lug 101 and a stationary extension 107 of the transmission casing.

The transmission casing 16, which carries the roll and shoe structures may be secured to the table 18 by any suitable means. Preferably an angle iron structure 110 is bolted, by bolts 111 to the casing 16. This angle iron structure is secured to the table supports by any improved manner, and preferably extends longitudinally along each long edge of the table from one leg to the other, to provide a rigid support for the ironing mechanism.

In the operation of the machine and assuming that the motor has been placed in motion with the manipulator 14 and slide 72 in the position thereof shown in Fig. 14, shaft 64 and gear 68 are rotated. In this position of the pedal or

manipulator 14, no motive power is transmitted to roll 11 due to the fact that neither of the running wheels 66 and 68 are held, by stop rods 67 and 69, against rotation and the station clutch transmission maintains the shoes 12 and 13 in a position away from the roll. Upon placing work in association with roll 11 to be ironed, the pedal 14 is depressed to its first position of the depression as shown in Fig. 15. This movement of pedal 14 lowers the slide 72, permits lever 52 to rotate crosswise and set the station clutch transmission in motion to move both or one or the other of the shoes 12 and 13 into engagement with the roll 11 while at the same time operating one of the levers 67 or 69 into engagement with one of the wheels 66 or 68 so that power is transmitted from the motor to the roll shaft 17 to rotate the roll at one or a first speed. The material to be ironed is started between the shoes 12 and 13 and the roll 11 and if it is desired to increase the speed of the roll, the pedal 14 is again depressed to its second position of depression as shown in Fig. 16. This further depressed position of the pedal 14 causes slide 72 to axially rotate the levers 67 and 69 so that the one lever will be disengaged from holding position and the other will be brought into engagement with its associated toothed wheel to thereby cause rotation of the larger gears 81 to drive the spider 80 and consequently the roll shaft 17 at a second or increased speed. When the ironing operation is finished, pedal 14 is released. Release of the user's foot from pedal 14 renders the spring 100 effective to move the slide 72 and pedal 14 upwardly to the normal position as shown in Fig. 14 and the motor still being operated will, through the station clutch transmission, cause the shoes 12 and 13 to move back away from roll 11 in order to place the ironing machine in readiness to receive further work to be ironed or pressed. The indexing means, which conveys to the user's foot on pedal 14 sensations to render the user conscious of the various operating positions of the slide to carry out the functions of the machine, permits the user to reverse the operations of the machine described or to carry these operations forward selectively as may be desired. If it is desired to press clothes without rotation of the roll 11, such clothes are placed on the roll, and the pedal is depressed to the position shown in Fig. 17. This places the levers 67 and 69 in a position to maintain the roll stationary and moves the lever 51 to a position to rock the shoe or shoes to press the clothes. Thus the plurality of functions of the machine, through the medium of the gear transmission, station clutch transmission and connections with the slide, may be caused to be carried out by a single control or manipulator.

While the form of embodiment of the invention as herein disclosed, constitutes a preferred form, it is to be understood that other forms might be adopted as may come within the scope of the claims which follow.

What is claimed is as follows:

1. In a machine of the character described, a rotatable driving shaft, a station clutch driven by said driving shaft to a plurality of positions, a control member for said station clutch having stop arms rotatable in different planes, and a movable stop member movable selectively into said different planes.
2. In a machine of the character described, a rotatable driving shaft, a station clutch driven by said driving shaft to a plurality of positions, a control member for said station clutch having

stop arms rotatable in different planes, a movable stop member movable selectively into said different planes, a variable speed transmission driven by said driving shaft and driving a rotatable driven shaft at a plurality of speeds, control means for said transmission movable to a plurality of positions to cause said rotatable driven shaft selectively to be driven at a selected speed, and a unitary manipulator having lost motion connection with said stop member and control means to permit control of said transmission simultaneously with, and independently of, said station clutch.

3. In a machine of the character described, a rotatable driving shaft, a station clutch driven by said driving shaft into positions substantially 180° apart, a control member for said station clutch having two stop arms rotatable with said station clutch in different planes, and a movable stop member movable selectively into said different planes.

4. In a machine of the character described, a rotatable driving shaft, a station clutch driven by said driving shaft into positions substantially 180° apart, a control member for said station clutch having two stop arms rotatable with said station clutch in different planes, a movable stop member movable selectively into said different planes, a rotatable driven shaft, a transmission connecting and disconnecting said driving and driven shafts, a control means for said transmission movable to a plurality of positions to cause said transmission to connect and disconnect said shafts, and a unitary manipulator having lost motion connection with said stop member and control means to permit control of said transmission simultaneously with, and independently of, said station clutch.

5. In a machine of the character described, a rotatable driving shaft, a sun gear fixed on said driving shaft, a driven shaft, a planetary gear frame fixed to said driven shaft, a first planetary gear carried by said frame having a first diameter and being in permanent engagement with said sun gear, a second planetary gear fixed to said first planetary gear and having a second diameter different from said first diameter, a first idler ring having geared engagement with said first planetary gear, a second idler ring having geared engagement with said second planetary gear, a first control means movable into and out of stopping engagement with said first idler ring, a second control means movable into and out of stopping engagement with said second idler ring, a station clutch driven by said driving shaft into positions substantially 180° apart, a control member for said station clutch having two stop arms rotatable in different planes, and a unitary manipulator having lost motion connection with said first and second control means and with said control member to permit control of the rotation of said driven shaft simultaneously with, and independently of, said station clutch.

6. In a machine of the character described, a rotatable driving shaft, a rotatable driven shaft, a transmission between said shafts drivingly to engage and disengage said shafts, a station clutch movable into at least two positions by said driving shaft, and a unitary manipulator having lost motion control connections with said transmission and station clutch to cause, by movement of said manipulator in a single direction and while said driving shaft is rotating, said station clutch to move to a selected position and selectively to engage and to disengage said shafts.

7. In a machine of the character described, a

rotatable driving shaft, a rotatable driven shaft, a variable speed transmission between said shafts to engage and disengage said shafts to rotate said driven shaft at variable speeds and to stop said driven shaft independently of rotation of said driving shaft, a station clutch movable into at least two positions by said driving shaft, and a unitary manipulator having lost motion control connections with said transmission and station clutch to cause, by movement of said manipulator in a single direction and while said driving shaft is rotating, said station clutch to move to a selected position and selectively to drive said driven shaft at varying speeds and to disengage said shafts.

10 8. In a machine of the character described, a member to be reciprocated, a cam sleeve connected to said member, a cam within said sleeve, a one-way clutch between said cam and sleeve to lock said cam against backward movement relative to said sleeve, a station clutch operatively connected with said cam including a ratchet wheel adapted to rotate continuously, a pawl slidably mounted on said cam, and means to engage and disengage said pawl and ratchet wheel to move said cam to and from station positions.

15 9. In a machine of the character described, a member to be reciprocated in a plane, a cam sleeve connected to said member and adapted to be gyrated about an axis in said plane, a cam within said sleeve mounted on a shaft coaxial with said axis, a one-way clutch between said cam and sleeve to lock said cam against backward movement relative to said sleeve, a station clutch operatively connected with said cam including a ratchet wheel adapted to rotate continuously about said axis, a pawl slidably mounted on said cam, and means to engage and disengage said pawl and ratchet wheel to move said cam to and from stations lying substantially in said plane.

20 10. In a machine of the character described, a body to be reciprocated, a cam sleeve connected to said body, a cam within said sleeve, a one-way clutch between said cam and sleeve to lock said cam against backward movement relative to said sleeve, a station clutch operatively connected with said cam including a ratchet wheel member and a pawl member, one of said members being slidably mounted on said cam and the other of said members being adapted to rotate continuously, and means to engage and disengage said pawl and ratchet wheel members to move said cam to and from station positions.

25 11. In a machine of the character described, a driving shaft rotatable about an axis, a driven shaft rotatable about said axis, a cam rotatable about said axis, planetary gearing between said shafts, control means for said gearing causing said driving shaft drivingly to engage and rotate said driven shaft at varying speeds and to disengage said shafts, a station clutch between said driving shaft and cam, control means for said station clutch causing said driving shaft to move and stop said cam between selected stations, an unitary manipulator having connections with said two control means, one of said connections being a lost motion connection.

30 12. In a machine of the character described, a driving shaft rotatable about an axis, a driven shaft rotatable about said axis, a cam rotatable about said axis, transmission mechanism between said shafts, control means for said transmission mechanism causing said driving shaft drivingly to engage said driven shaft and to dis-

engage said shafts, a station clutch between said driving shaft and cam, control means for said station clutch causing said driving shaft to move and stop said cam between selected stations, and a unitary manipulator having connections with said two control means, one of said connections being a lost motion connection.

13. In a machine of the character described, a rotatable driving shaft, a rotatable driven shaft, a rotatable cam, transmission mechanism between said shafts, a movable control member for said transmission mechanism causing said driving shaft drivingly to engage said driven shaft and to disengage said shafts, a station clutch between said driving shaft and cam, a movable control member for said station clutch causing said driving shaft to move and stop said cam between selected stations, and a unitary actuator having irregularities engaging said movable control members at different positions of said actuator.
